(57) **CLAIM**

The ornamental design for a mobile radio, as shown and described.

DESCRIPTION

FIG. 1 is a front, top and right side perspective view of a mobile radio showing our new design;

FIG. 2 is a top view thereof;

FIG. 3 is a bottom view thereof;

FIG. 4 is left view thereof;

FIG. 5 is a right view thereof;

FIG. 6 is a back view thereof; and,

FIG. 7 is a front view thereof.

The broken lines shown in FIGS. 1-7 are included for the purpose of illustrating environmental elements only and form no part of the claimed design. The broken lines, which define the boundary of the claimed design form no part thereof.
